UNITED STATES PATENT OFFICE.

JAMES O'FRIEL, OF BROOKLYN, NEW YORK.

FIRE-PROOF FLOOR AND CEILING FOR BUILDINGS.

SPECIFICATION forming part of Letters Patent No. 298,227, dated May 6, 1884.

Application filed April 23, 1883. (No model.)

To all whom it may concern:

Be it known that I, JAMES O'FRIEL, of Brooklyn, in the county of Kings and State of New York, have invented an Improvement in 5 Fire-Proof Floors and Ceilings for Buildings, of which the following is a specification.

Buildings have been made with iron beams and cement slabs between such beams, resting upon the flanges of the beams. There are two 10 sources of difficulty in constructing these floors. The first arises from the fact that it becomes necessary to hold up against the iron beams a platform or table upon which the plastic cement is poured and rammed, and to 15 effect this object horses and underpinning have been necessary. These interfere with workmen proceeding with other work in the rooms where the ceiling is being formed, and in the removal of these horses or underpinning and 20 the lowering of the platforms the walls and other portions are liable to injury. The second difficulty arises from the fact that slabs of cement, while in the process of hardening, are very liable to injury, while the same block 25 after it hardens will be more than ample for withstanding all the strain or concussion to which it may be subjected.

The object of my present invention is to remove both these difficulties; and it relates to 30 a peculiar manner of constructing the movable table and the supports for the same, so that they may be clamped to the beams themselves and raised or lowered with facility from above, so that the room below the floor or ceiling that 35 is being laid will be free from obstruction while the cement is being laid and sets or hardens, and also to the manner in which the cement itself is strengthened, so that it can withstand the jar or pressure to which it is subjected 40 after the table has been removed from below it and during the hardening operation. In consequence of the last-named improvement I am able to remove the tables from below the cement much earlier than it would be safe to 45 do with cement ceilings laid in the ordinary manner, and by the first-named improvement the tables can be applied to or removed from the beams without unnecessary delay, and the risk of injury to the cement floor is reduced 50 to a minimum.

In the drawings, Figure 1 is a cross-section

of the beams and tables. Fig. 2 is a section longitudinally representing the cement in the progress of laying, and Fig. 3 is a partial plan.

The beams *a a* are of iron of any desired 55 cross-sectional shape, and of the required strength. These are put into the building in the usual manner.

I provide numerous tables, *b b*, which are by preference of a width to extend from the center of one beam *a* to the center of the next, or nearly so, and of a length that is convenient for handling—say six or eight feet—so as not to be too heavy. I, however, remark that these tables may be wide enough to include 65 three beams, if desired. Each of these tables is to be smooth upon the upper surface and provided with the necessary battens or strips upon the under side to make a firm and strong table.

I provide bearers *d d*, that are longer than the distance from one beam *a* to the next, so as to rest upon such beams *a* securely, and in each of said bearers there are one or more notches of a width adapted to receive the clamping 75 screw-bolts *e*. These screw-bolts *e* pass up through the table. There may be one or more of such screws to each table, according to the size of such table, and each screw is provided with a nut or with a head at *i* below the table, 80 and with a nut, *k*, upon the upper part of the screw. There is a conical thimble, *l*, around each screw, and an eye or hook at the upper end of each screw. This eye or hook *n* is either in the end of the bolt itself, or by preference in the form of a yoke or turn-buckle to the nut, as shown. The workmen place upon the beams *a* movable planks, so as to give footing in placing the tables, and the tables are drawn up from below by ropes or chains 90 hooked into *n*. The bearers *d* are passed beneath the nuts *k*, the screw-bolt entering the vertical notch. Then the nuts are screwed up to clamp the tables securely against the under surfaces of the beams *a a*, care being taken 95 to have the tables in their proper positions relatively to the beams, and the desired number of tables are to be put into place and securely clamped. The slab of artificial stone is made between the beams by filling in to the 100 desired depth with cement—such as Portland cement—with sand, gravel, or broken stone, or

plaster-of-paris, or any suitable cement compound. The depth to which the cement is to be filled is indicated by the height of the thimbles *l*, the cement not being filled above the top of said thimbles. I also introduce thwarts *t* at suitable distances apart, said thwarts resting at their ends upon the flanges of the iron beams, and being embedded into the cement, the cement above said thwarts forming a ridge or rib crossing from one beam to the next. These thwarts are to be either of wood or iron. If of wood, they cannot burn, as they are entirely incased. The object of these thwarts is to stiffen the slab of artificial stone and aid in keeping it from injury while the cement is in a moist condition before it becomes entirely consolidated and dry.

When one section of the flooring is sufficiently set to be self-supporting, the table can be lowered and used elsewhere. To lower the table, the nut *k* only requires to be slackened and the cross-bearer *d* removed from beneath it, and a hook at the end of a rope is hooked into the eye or hooks *n* and the table and bolt or bolts lowered, and the conical thimble *l* will pull down out of the slab of cement and leave a hole therein sufficiently large to allow the eye or hooks to pass through freely. The rope is unhooked after the table has been lowered to the floor below. Then the rope is drawn up, and the table transported to the place where it is next to be used, and drawn up to the beams and secured, as before. The hole that is left by the drawing out of the conical thimble is to be filled with cement by hand.

I do not claim a centering or arch between the beams supported by timbers below and bolts passing through cross-bearers above, as this has been done; but the bolts become fast

in the cement, and no provision is made for attaching ropes to the bolts and lowering the centering or timbers. By my improvement the holes in the cement are made sufficiently large for passing the bolts and the eyes for the ropes by which the tables are lowered.

45

I claim as my invention—

1. The combination, with the beams and table, of the cross-bearer, the bolt, nuts, eye, and thimble, substantially as set forth.

2. The method herein specified of making slabs of artificial stone between iron beams, consisting in drawing up to the under side of the beams tables and clamping them by means of bolts and bearers, filling in the space between the beams by a cement resting upon the tables, and forming holes through the cement by thimbles around the bolts, and then lowering the tables, after the cement has hardened, by ropes connected to the bolts and passing through the holes in the cement, substantially as set forth.

3. In the formation of slabs of artificial stone between iron beams, the combination, with the cement, of thwarts resting at their ends upon the iron beams and incased in the cement, substantially as and for the purposes set forth.

4. In combination with the tables *b* and the bolts *e*, the nuts upon such bolts, and eyes at their upper ends for ropes to be connected to, and the notched cross-bearers resting upon the beams, substantially as set forth.

Signed by me this 19th day of April, A. D. 1883.

JAMES O'FRIEL.
